UNITED STATES PATENT OFFICE

117,045

DESIGN FOR A BUMPER GUARD OR SIMILAR ARTICLE

Herbert S. Jandus, Detroit, Mich., assignor to Houdaille-Hershey Corporation, Detroit, Mich.,
a corporation of Michigan

Application August 19, 1939, Serial No. 86,782

Term of patent 7 years

To all whom it may concern:

Be it known that I, Herbert S. Jandus, a citizen of the United States and a resident of the city of Detroit, in the county of Wayne and State of Michigan, have invented a new, original, and ornamental Design for a Bumper Guard or Similar Article, of which the following is a specification, reference being had to the accompanying drawing, forming a part thereof.

On the drawing:

I claim:

The ornamental design for a bumper guard or similar article, as shown.

HERBERT S. JANDUS.
